UNITED STATES PATENT OFFICE.

JACOB SKLAR, OF PHILADELPHIA, PENNSYLVANIA.

WATER-HEATER.

1,127,532.

Specification of Letters Patent.

Patented Feb. 9, 1915.

Application filed November 16, 1914. Serial No. 872,418.

To all whom it may concern:

Be it known that I, JACOB SKLAR, a subject of the Czar of Russia, residing at Philadelphia, in the county of Philadelphia and 5 State of Pennsylvania, have invented certain new and useful Improvements in Water-Heaters, of which the following is a specification, reference being had to the accompanying drawings.

10 This invention relates to certain improvements in water heaters and has relation more particularly to a device of this general character especially designed and adapted for use for household purposes; and an object 15 of the invention is to provide a heater of this general character having novel and improved means whereby the water or other liquid may be heated to the required temperature with convenience and facility.

20 Furthermore, it is an object of the invention to provide a novel and improved device of this general character including means whereby a face thereof is provided with a heat insulating medium in order to protect 25 a person employing the device.

It is also an object of my invention to provide a device of this general character having novel and improved means whereby the 30 requisite heat may be generated from different sources and whereby the heat thus generated may be readily and effectively controlled.

The invention consists in the details of 35 construction and in the combination and arrangement of the several parts of my improved water heater whereby certain important advantages are attained and the device is rendered simpler, less expensive and otherwise more convenient and advantageous 40 for use, all as will be hereinafter more fully set forth.

The novel features of the invention will be carefully defined in the appended claims.

In order that my invention may be the 45 better understood, I will now proceed to describe the same with reference to the accompanying drawings, wherein—

Figure 1 is a vertical transverse sectional view taken through a heater constructed in 50 accordance with an embodiment of my invention; Fig. 2 is a longitudinal vertical section taken through the device as herein set forth, the supporting means therefor being omitted; Fig. 3 is a fragmentary enlarged 55 view in top plan of the bottom of the hollow body herein included; Fig. 4 is a fragment-

ary enlarged elevational view of one end of the body, illustrating certain details herein included; and Fig. 5 is an enlarged fragmentary sectional view illustrating other details of the invention as herein embodied.

As disclosed in the accompanying drawings, 60 1 denotes a hollow body of predetermined configuration supported in an operative position through the medium of the 65 yokes 2 and operatively positioned within said body is a container 3, the walls whereof being spaced a predetermined distance from the adjacent walls of the body 1 in order to afford a heating chamber C. As 70 herein embodied, the upper marginal portions of the container 3 are operatively engaged with the upper marginal portions of the body 1 in any conventional manner while the upper or open face of the container is 75 adapted to be closed by the lid or cover 5. The bottom wall 6 of the body 1 at substantially its transverse center is provided with an elongated depression 7 provided with the perforations 8 to permit admission 80 of air within the chamber C and to also serve as a fire box to permit the use of a coal or wood fire as the occasion may require. The fuel is adapted to be properly placed within the depression 7 through the opening 85 8 produced in the lower portion of the end wall 9, said opening 8 being under control, as herein embodied, of the swinging door 10.

While the depression 7 permits the use of a fuel such as coal or wood, it is a particular 90 object of my invention to provide means whereby a gaseous or liquid fuel may be employed. For this purpose I have positioned within the chamber C immediately below the container 3 a burner 11 of a formation which best suits the requirements of practice and having in communication therewith a fuel supply pipe 12 leading from a suitable source of supply and projecting through the opening 8. The door 103 10 is provided in one of its corners with a recess 14 to receive the pipe 12 so that no obstruction will be offered in opening the door, as is believed to be clearly apparent to those skilled in the art to which my invention appertains. The rear wall 15 of the body 1 at its upper marginal portion is provided with the outwardly disposed depression 16 adapted to afford a flue or vent 105 through which the heat within the compartment C may be discharged and in order to control the discharge through such flue or 110

vent, I have operatively supported therein a damper D of any ordinary or preferred arrangement and operating in a manner which is believed to be self-evident.

- 5 As herein set forth, my invention is shown applied to a wash-tub or the like and in order to protect the person using the device from the heat generated within the chamber C, I find it of advantage to apply in 10 connection with the front wall 17 of the body 1 and within the chamber C, the member 18 of predetermined dimensions which serves to afford a space S which serves as a heat insulating medium. While the member 15 18 may be operatively engaged with the front wall 17 in any desired manner, I find it of advantage to employ the headed members 19 disposed inwardly through the front wall 17 of the body 1, with their inner extremities in threaded engagement with the member 18 and in order to maintain such member 18 in the required spaced relation relative to the front wall 17, I surround the headed members 19 with the sleeves or barrels 20 interposed between the inner face of the outer wall 17 and the member 18, as is believed to be obvious.

From the foregoing description, it is thought that a water heater constructed in 30 accordance with my invention is of an extremely simple and comparatively inexpensive nature and is particularly well adapted for use by reason of the convenience and facility with which it may be assembled, and it will also be obvious that my invention 35 is susceptible of some change and modifica-

tion without material departure from the principles and spirit thereof and for this reason I do not wish to be understood as limiting myself to the precise arrangement 40 and formation of the several parts herein shown in carrying out my invention in practice.

I claim:

1. A device of the character described 45 comprising a hollow body, a container supported thereby and positioned therein, the opposed walls of the body and container being in spaced relation to afford a heating chamber, the bottom wall of the body having one extremity provided with a longitudinally disposed depression provided with 50 perforations, an end wall of the body being provided with an opening in communication with the depression, and a door for closing 55 said opening.

2. A device of the character described comprising a hollow body, a container supported thereby and positioned therein, the opposed walls of the body and container being in spaced relation to afford a heating chamber, the bottom wall of the body being 60 perforated, said body having a wall provided with an outwardly disposed depression to afford a flue.

In testimony whereof I hereunto affix my signature in the presence of two witnesses.

JACOB SKLAR.
